ERNEST LEGON, OF SAULT STE. MARIE, ONTARIO, CANADA.

TRACK-GAGE.

1,242,210.

Specification of Letters Patent.

Patented Oct. 9, 1917.

Application filed November 7, 1916. Serial No. 129,991.

To all whom it may concern:

Be it known that I, ERNEST LEGON, a citizen of the United States, residing at Sault Ste. Marie, in the Province of Ontario and Dominion of Canada, have invented certain new and useful Improvements in Track-Gages; and I do hereby declare the following to be a full, clear, and exact description of the invention, such as will enable others skilled in the art to which it appertains to make and use the same.

This invention relates to a track gage and has for its primary object the provision of means whereby it may be readily determined if the parallel rails of a track are in a horizontal plane and if not, what degree of an angle the rails are occupying in relation to each other, also whereby the tread surfaces of the rails may be gaged to determine if they are in a common plane.

Another object of this invention is to provide a base having means for securing it upon one of the rails of a track against horizontal movement and having a beam pivoted thereto and which may be locked thereto when desired and having means upon its free end to secure the same to the other rail of the track.

A further object of this invention is to provide a vertical gage plate upon the base having a weighted indicator pivoted to one side thereof and an indicator carried by the pivoted end of the beam and extending upwardly upon the opposite side of the plate, whereby the parallel rails of a track may be gaged to determine if they are in horizontal alinement and if not, what degree of an angle they are occupying in relation to each other.

A still further object of this invention is the provision of a track gage of the above stated character, which shall be simple, durable and efficient and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which,

Figure 1 is a side elevation of a track gage, constructed in accordance with this invention,

Fig. 2 is a top plan view of the same, 60

Fig. 3 is a detail sectional view taken on the line 3—3 of Fig. 2 illustrating the indicator,

Fig. 4 is a detail sectional view illustrating the means of locking the beam to the 65 base, and

Fig. 5 is a vertical sectional view taken on the line 5—5 of Fig. 1.

Referring in detail to the drawing, the numeral 1 indicates one rail of a track and 70 the numeral 2 indicates the other rail of the track which are usually secured to rail ties in parallel relation to each other.

A base 3 of elongated formation has secured to each side thereof L-shaped arms 4, 75 which have their free ends bent at right angles as illustrated at 5 to engage the inner face of the rail 1. Bolted or otherwise secured to one end of the base 3 is a spring clip 6 which engages the outer face of the 80 rail 1. The spring clip 6 cooperates with the right angled ends 5 of the L-shaped arms 4 in retaining the base 3 upon the rail 1 against longitudinal movement. The inner end of the base 3 is slotted as illustrated 85 at 7 and has pivotally secured therein one end of a beam 8 as illustrated at 9. The beam 8 is of sufficient length to reach the rail 2 and rests upon the same as clearly illustrated in Fig. 1. A downwardly de- 90 pending flange 10 is formed upon the free end of the beam 8 for engagement with the outer face of the rail 2. Slidable upon the beam 8 is a block 11 adapted to be moved into engagement with the inner face of the 95 rail 2 and held against longitudinal movement upon the beam 8 by means of a leaf spring 12 having its free ends bent to form a hook 13 which engages the vertical notches 14 arranged upon one side of the block 11. 100 The leaf spring 12 is secured to the free end of the beam 8 by means of a bolt 15 and is offset as illustrated at 16 so that the hook 13 may engage the vertical notches 14.

A vertical gage plate 17 is formed integrally upon the base 3 and has graduations adjacent its upper end and upon each side thereof. The zero mark 18 being located at a point central of the edges of the vertical gage plate and the graduations increasing upon each side thereof as clearly illustrated in Fig. 1. An indicator 19 is

pivoted to the gage plate 17 upon one side thereof as illustrated at 20 and has secured to one end a weight 21 for normally maintaining the indicator 19 in a vertical plane. 5 An indicator 22 is formed upon the pivoted end of the beam 8 and extends upwardly upon the opposite side of the gage plate 17 from the indicator 19. A pair of relatively spaced ears 23 are formed upon the inner 10 end of the base 3 and upon one side of the slot 7 to slidably receive a pin 24 which is adapted to be inserted through an aperture in the beam 8 and into an ear 25 formed upon the inner end of the base 3 and located 15 upon the opposite side of the slot 7 from the pair of ears 23 to lock the beam 8 against pivotal movement in relation to the base 3.

In operation, a person inserts the pin 24 20 through the beam 8 locking it against pivotal movement in relation to the base 3 and by walking along the track where the same is laid in a straight path, the person or user of the device to determine if the rails 1 and 25 2 are in a horizontal plane with each other places the base 3 upon one rail and allows the beam 8 to rest upon the other rail of the track. If the rails are not in a horizontal plane with each other, by pressing down- 30 wardly upon the beam 8 so that it rests evenly upon the rail on which it is positioned the base 3 is caused to incline at an angle upon the other rail of the track and the weighted indicator 19 will normally occupy a vertical position and as the base 3 is 35 inclined the gage plate will be inclined thereby causing the indicator to point to the degree of angle upon the gage plate which the base 3 is occupying thereby determining 40 at what degree of angle the rails are out of horizontal alinement with relation to each other. By moving the block 11 into engagement with the inner face of one of the rails, the device will be secured upon the track 45 whereby the operator or user of the device may release the device and elevate that rail which may be below the horizontal plane until the rails are moved into a horizontal plane with each other. The ties which are 50 under the rails at this point are raised upon the side of the track which is the lowermost and ballast placed thereunder so as to support the rails in a horizontal plane with each other. When the device is being used upon 55 a curve in a track and where it is necessary to incline the rails at an angle in relation to each other, the pin 24 is removed from the beam 8 so that the same may have pivotal movement in relation to the base. The base 60 3 is positioned upon one rail and the beam 8 upon the other rail and knowing at what degree the angle of the rails should be in relation to each other, it may be readily determined if correct, by the indicator 22 65 pointing to a correct degree upon the grad-

uation upon the gage plate 17. When the beam 8 is allowed pivotal movement in relation to the base, the common plane of the bearing surfaces of the rails may be also determined, by placing the base 3 so that the same rests flat upon one rail, the weighted indicator 19 indicating upon the graduations upon the gage plate 17 if the bearing surface upon the rail is in a correct plane or not. The bearing surfaces upon rails are sometimes caused to be out of a common plane by irregular ties used to support the rails.

While I have shown and described the preferred embodiment of my invention, it 80 will be understood that minor changes in construction, combination and arrangement of parts may be made without departing from the spirit and scope of the invention as claimed.

Having thus described my invention what I claim is:

1. A track gage comprising a base adapted to engage one rail of a track, a beam pivoted to said base and adapted to engage the 90 other rail of the track and means carried by the base and the beam to determine if the parallel rails of a track are in a horizontal plane with each other.

2. A track gage comprising a base, means 95 for securing said base upon a rail, a beam pivoted to said base and adapted to rest upon another rail, and means carried by the base and the beam to determine if the rails of a track are in a horizontal plane with 100 each other.

3. A track gage comprising a base, substantially L-shaped arms formed on said base and having their ends bent at right angles to engage the inner face of a rail, a 105 spring clutch secured to the base for engaging the outer face of said rail, a beam pivoted to said base and resting upon another rail, and means carried by the base and beam for determining if the rails are in a 110 horizontal plane with each other.

4. A track gage comprising a base, means for securing said base upon a rail, a beam pivoted to said base and adapted to rest upon another rail, a flange formed upon 115 said beam and adapted to engage the outer face of the second mentioned rail, a block slidably upon the said beam, and means for locking the block in engagement with the inner face of the second mentioned rail, and means carried by the base and beam for determining if the rails are in a horizontal plane with each other.

5. A track gage comprising a base, means for securing said base to a rail, a beam pivoted to said base and adapted to rest upon another rail, a flange on said beam and adapted to engage the outer face of the second mentioned rail, a block slidably upon 120 said beam and having a plurality of vertical 125

notches, and a leaf spring secured to the beam and engaging the notches for locking the block in engagement with the inner face of the second mentioned rail, and means 5 carried by the base and the beam for determining if the rails are in a horizontal plane with each other.

6. A track gage comprising a base, means 10 for securing said base to a rail, a beam pivoted to said base and adapted to rest upon another rail, means for securing the free end of the beam to the second mentioned rail, means for locking the beam against pivotal movement with relation to the base, 15 and means carried by the base and the beam for determining if the rails are in a horizontal plane with each other.

7. A track gage comprising a base, means

for securing said base to a rail, a beam pivoted to said base and adapted to rest upon 20 another rail, a gage plate secured to said base, and having graduations upon each side thereof, a weighted indicator pivoted to one side of the gage plate, and an indicator formed upon the pivotal end of the beam 25 for coöperation with the weighted indicator to determine if the rails are in a horizontal plane with each other.

In testimony whereof I affix my signature in presence of two witnesses.

ERNEST ^{his} X LEGON.
